UNITED STATES PATENT OFFICE.

ROBERT ALEXANDER STEPS, OF LOS ANGELES, CALIFORNIA.

SCREEN FOR CENTRIFUGAL BASKETS.

Application filed March 30, 1923. Serial No. 628,944.

To all whom it may concern:

Be it known that I, ROBERT ALEXANDER STEPS, a citizen of the United States, residing at Los Angeles, in the county of Los Angeles and State of California, have invented a new and useful Screen for Centrifugal Baskets, of which the following is a specification.

This invention relates to screens such as are used in centrifugal baskets, and which are formed of a foraminous sheet bent into a substantially cylindrical shape, the two abutting edges being then more or less fastened together in some suitable manner.

Heretofore there have been various ways of fastening these edges, but for several reasons none of these modes of fastening have been altogether satisfactory.

As is well understood the material such as sugar, for instance, which is treated in these centrifugal baskets, is finally discharged therefrom by means of a discharging shoe, the sharp tip or point of which presses on the screen as the latter revolves with the basket slowly, during the discharging operation, thereby cutting the sugar or other material off the screen and discharging it through the bottom of the basket in a well known manner. As the discharging proceeds this shoe is gradually lowered along the screen by mechanical means, until all the material is presently discharged by the action of this descending shoe scraping on the slowly revolving screen and basket.

Owing to this scraping action which the discharging shoe necessarily has on the screen, the mode in which the aforesaid abutting edges of the latter are joined together, must comply with some rather rigorous conditions which have not been well complied with in any of the joints heretofore proposed. In the first place the joint should be as flat as possible, i. e., it should not be "bunchy" as occurs when the character of the joint involves too many layers of the sheet in making it, as the latter produces a thick awkward joint that bumps against the discharging shoe each time it comes around, in place of moving smoothly by and under it as would be the case if the joint were very flat and in no sense "bunchy." And in the second place the joint should be such as to present no upstanding edge that could be cut or encountered by the downward movement of the shoe any more than it should present any upstanding edge that

could be cut or encountered by the relative circumferential movement between the joint and the shoe. It is true that screens heretofore proposed have no edges that encounter the shoe in the circumferential direction, but most of them have upstanding edges that freely encounter and cut against the shoe in its downward direction, and since the latter is fully as important as the former, it is clear that the screens so proposed have only poorly solved the problem which confronted them.

By a novel combination and rearrangement which I will now describe, my invention has the double advantage of getting away from the objectionably thick "bunchy" joints that have heretofore been known, and at the same time getting away from any upstanding edge that could encounter the discharging shoe either in its relative downward or circumferential movement, and while securing these extremely important advantages my invention further results in the very simplest possible kind of a joint, and perfectly satisfies all operating conditions or difficulties that could be encountered.

In the drawings Fig. 1 illustrates the foraminous sheet flattened out, part of the sheet being broken away for space economy. Fig. 2 is an enlarged view showing the two edges to be joined. Fig. 3 is a similar view after the edges are joined. Fig. 4 is a plan view looking down on the joint. Fig. 5 shows the foraminous sheet bent into cylindrical shape and joined, the discharger shoe being indicated more or less diagrammatically in its relation to the screen. Fig. 6 is a more or less diagrammatic view showing the discharging shoe cutting the sugar or other material off the screen. Fig. 7 shows the edges about to be joined, but in this case illustrating a modified form of my invention. Fig. 8 shows the joint when completed in accordance with the modification shown in Fig. 7.

In Fig. 3 the metal on one side of the joint has been shaded by light horizontal lines, while the metal on the other side of the joint has been shaded by light lines running at an angle, as it is thought that this shading will more clearly point out the limits of the metal and also the character of the joint when completed.

Also it will be understood that the sheet shown in these drawings is perforated by a great number of very fine holes so it can act like a screen permitting the liquid to pass

through same, but retaining the solid material, such as sugar crystals, inside the screen during the centrifuging treatment. These perforations have been partially indicated in Fig. 1, but have been omitted from all other figures in the interest of clearness and simplification.

In equipping this screen or foraminous sheet with my new joint it is only necessary 10 to slit the one edge B into a series of substantially horizontal tongues b, the same being practically contiguous with each other, and to form near the other edge A a slot a for each of the tongues b, these slots a being slanted with reference to a vertical direction.

Broadly speaking there was of course no invention in merely using tongues along the one edge and some sort of slots along the 20 other edge, as tongues and slots are an extremely old and primitive fastening expedient wherever it is desired to more or less join together two overlapping surfaces, but by the particular idea of slanting the slots a in the manner indicated I have brought forth a joint that has a new and particularly useful advantage in connection with these 25 centrifugal screens.

As indicated in Figs. 2, 3, and 4, each of 30 the tongues b need merely be pushed through the slanted slot a provided for it and the joint is complete, and has the appearance shown in Figs. 3 and 4. In doing this the tongues are inserted through the slots from 35 the inside of the cylinder outwardly, which leaves the inside where the sugar and other material is accumulated practically smooth as the tongues are all on the outside of the sheet.

40 Heretofore where a series of tongues have been used, slots were only provided for each alternate tongue, and the edges were then overlapped and interwoven by passing half of the tongues over the abutting edge and 45 through the slots, and the other half of the tongues under the abutting edge, but examination of the joints having these interwoven edges shows them to be very thick and "bunchy" on account of the several thicknesses of metal which this interweaving of 50 the edges gives, which is rendered more objectionable in view of the tendency of the metal to resist flattening or smoothing out of the oppositely directed curvatures which 55 this interweaving action produces on the tongues.

My tongues however receive no such opposite curvatures in respect to each other, as 60 they are all treated alike, and are merely pushed straight through the opposite slots, which involves no interweaving action and consequently results in a very flat thin joint that can be easily smoothed out to a condition of no appreciable thickness over the 65 single layer of metal on either side of the

joint. In fact it is practically unnecessary to attempt any such smoothing, as neither the tongues on the one side, nor the edge with the slots on the other side, are bent in making the connection, with the result that 70 the joint is not accompanied with the "bunchiness" that characterizes other joints.

I will now describe the excellent manner in which this joint is adapted to co-operate with the discharging shoe.

75 Figs. 5 and 6 indicate the discharging shoe at c, and as is well known the sharp tip or edge of this shoe is pressed against the screen by the impact of the sugar wall d, as the sugar revolves with the screen and basket in direction of arrow 1 and encounters the shoe c which is mechanically held in the approximate position shown in Fig. 6.

80 As the sugar is cut out from the upper portion of the basket, the shoe is mechanically lowered to continue the cutting action, this lowering being accomplished by well known mechanisms known as "dischargers" which need not be described here as they 85 have no special connection with this invention.

Fig. 5 however, by means of arrow 1, indicates the circumferential rotation of the screen, and by means of arrow 2 indicates 90 the downward motion of the discharging shoe during operation, by virtue of which two motions a relative resultant motion in direction of arrow 3 results, and consequently so far as the screen is concerned the arrow 95 3 indicates the relative direction in which the shoe c passes over the screen and joint. The particular inclination of arrow 3 of course depends upon the speed of rotation of the screen in direction of arrow 1, and also 100 on the speed with which the shoe descends in direction of arrow 2, and both these factors being variable, the inclination of arrow 3 is more or less variable also, but the fact that it is inclined somewhat as indicated in Fig. 5 is obvious from the conditions mentioned.

105 With this established, attention is now directed to Fig. 3 which shows the joint on a sufficiently large scale so that the action of the discharging tip in passing over it can be best understood. Arrow 3, though probably excessively inclined, is applied to this figure to indicate the course of the discharging shoe over the joint.

110 As the sharp tip of the shoe moves along the arrow 3 it will be seen never to encounter an upstanding edge, as all the edges encountered run from higher surfaces on to lower surfaces, which is the ideal condition, as no 115 tearing or cutting of any sort can then occur between the screen at the joint and the sharp tip of the discharger as it moves over it. Taking any particular slot and tongue in Fig. 3, it will be seen that a member mov-

ing approximately in direction of arrow 3 will run off the metal *a* on to tongue *b*, and again off the metal *b'* at the lower edge of the tongue on to the metal *a'*, and in due course again off the metal *a* of the next lower slot on to the tongue *b* adjacent thereto, and in each of these cases the motion was always from a higher surface to a lower surface which illustrates the point I am making that no upstanding edge is encountered in passing over my joint in a downward direction, or in one circumferential direction, or in any resultant direction comprising a combination of these two. From what has already been stated it is clear that this is the ideal arrangement in view of the downward and crosswise direction in which the discharging shoe actually traverses the joint.

In conclusion, it may be fairly stated that the advantages hereinbefore stated, i. e., the advantage of an unusually thin flat joint, and also the advantage of unusually good adaptation to the passage of the discharger shoe over the joint, are both obtained largely by my idea of slanting the slots with reference to a vertical direction, and providing such a slot for practically every tongue.

Of course my invention can be applied with more or less modification as illustrated in Figs. 7 and 8, which has the advantage of making the slotted edge a little stronger, and no doubt no serious difficulty would be encountered if any one endeavored to apply my invention by making small modifications such as omitting a small number of the tongues, or perhaps a small number of the slots, or perhaps by failing to insert a small number of the tongues in the slots, but in the main the form which I have illustrated and described is the best mode in which I prefer to make and apply this invention.

I claim.

1. A centrifugal screen comprising a foraminous sheet adapted to be bent substantially into a cylinder, the edges of said foraminous sheet being held together by tongues formed along one edge, and by slots formed adjacent the other edge, the slots being slanted with reference to the axis of said cylinder.

2. A centrifugal screen comprising a foraminous sheet adapted to be bent substantially into a cylinder, the edges of said foraminous sheet being held together by tongues formed along one edge, and slots

formed near the other edge, the slots being slanted with reference to a vertical direction, and the tongues being inserted through said slanted slots from the inside of the foraminous cylinder outwardly so as to leave the inside of the cylinder substantially smooth.

3. A centrifugal screen comprising a foraminous sheet adapted to be bent substantially into a cylinder, the edges of said foraminous sheet being held together by tongues formed along one edge, and slanted slots near the other edge, the tongues being substantially contiguous to each other and formed by slits extending substantially horizontally along the metal sheet, and said slots being slanted with reference to a vertical direction, substantially all the tongues being inserted through said slanted slots from the inside of the cylinder outwardly so as to leave the inside of the cylinder substantially smooth.

4. A centrifugal screen comprising a foraminous sheet adapted to be bent into a cylinder, the edges of said sheet being held together by tongues on the one edge and slanted slots on the other edge, there being a slot for substantially every tongue, the said slots being slanted with reference to a vertical direction, and substantially all the tongues being inserted through said slanted slots from the inside of the cylinder outwardly so as to leave the inside of the cylinder substantially smooth.

5. A centrifugal screen comprising a foraminous sheet adapted to be bent substantially into a cylinder, one edge of said sheet being slit into a series of substantially horizontal contiguous tongues, and the opposite edge of said sheet having a slot for each of said tongues, the said slots and tongues being adapted to form a joint, the said slots being slanted with reference to a normal vertical direction, and each tongue being passed through one of said slanted slots from the inside of the cylinder outwardly so as to leave no upstanding edge that could impede a movement in a downward direction or in one circumferential direction across the joint.

Signed at Denver, in the county of Denver and State of Colorado, this 26th day of March, 1923.

ROBERT ALEXANDER STEPS.
